UNITED STATES PATENT OFFICE.

AUGUST HUND, OF BETHESDA, MARYLAND, ASSIGNOR TO WIRED RADIO, INC., OF NEW YORK, N. Y., A CORPORATION OF DELAWARE.

PIEZO-ELECTRIC-CRYSTAL OSCILLATOR SYSTEM.

Application filed May 10, 1927. Serial No. 190,303.

My invention relates broadly to high frequency oscillators and more particularly to a piezo electric crystal control system for generating high frequency oscillations.

5 One of the objects of my invention is to provide a circuit arrangement for the generation of high frequency oscillations under control of a piezo electric crystal element wherein means are provided for eliminating 10 back reactions in the circuits of an electron tube system which may be arranged for sustaining the oscillations.

Another object of my invention is to provide a circuit arrangement for a high frequency oscillator wherein a piezo electric crystal element is so connected with respect to the electrodes and circuits of the oscillator that sustained high frequency oscillations may be developed without interference from 20 circuit reactions normally encountered in oscillator circuits.

Still another object of my invention is to provide a circuit arrangement for a high frequency oscillator wherein the characteristic frequency of a piezo electric crystal element may be sustained independently of reactions which have a tendency to develop in the circuits of the oscillator for avoiding influence of circuit oscillations upon the 30 characteristic frequency of the piezo electric crystal element.

My invention will be more clearly understood by referring to the following specification and the accompanying drawings where- 35 in:

Figure 1 shows diagrammatically a piezo electric crystal controlled oscillator system embodying the principles of my invention; Fig. 2 illustrates a modified construction of 40 apparatus which may be employed in the circuit arrangement of my invention.

It can be shown theoretically as well as experimentally that a piezo-electric element is equivalent to a large inductance in series 45 with a resistance and a comparatively small capacity. In a piezo electric crystal controlled electron tube oscillating system the capacity of the crystal holder and that of the two tube elements (filament and grid or grid 50 and plate) must be considered. In other words, this equivalent circuit is as a whole shunted by a condenser taking into account the various other capacity effects. As far 55 as operation with radio frequencies goes, the effect is relatively small and substantially

negligible for all practical purposes. When the beat frequency between two piezo-electric elements is utilized any error is greatly magnified in the beat frequency $f_1 - f_2$ where f_1 and f_2 denote the two constituent radio 60 frequencies. It is a fact that any error in any of the two frequencies f_1 or f_2 is the same for the beat frequency $f_1 - f_2$ but the percentage error is

$$\frac{f_1 + f_2}{2(f_1 - f_2)}$$

65

times as large. It is therefore essential that any back action from the anode branch of a piezo electric oscillator be reduced to a minimum. My present circuit arrangement has been designed to avoid losses and interference due to back actions.

Referring to the drawings reference character 1 designates an electron tube having 75 cathode 2, grid electrode 3 and plate electrode 4. The cathode is heated by means of battery 5, the temperature being regulated through rheostat 6. The output circuit of the electron tube oscillator includes plate 80 electrode 4, inductance 7 and high potential battery 8. The output of the oscillator may be connected to any desired circuit which I have represented at 9. I have indicated the capacity 10 positioned across the batteries 85 5 and 8 for by-passing high frequency oscillations. A capacity 11 has been represented as connected across inductance 7, which capacity may be variable or designed to have a selected fixed value for sustaining 90 a particular frequency. A connection is provided from the grid electrode 3 to the upper electrode 12 of a piezo electric crystal apparatus which includes the upper electrode 12 and the lower electrode 14 with the piezo 95 electric crystal element 15 located therebetween. The lower electrode 14 connects to a cylindrical member 16 which may be moved to selected positions along the inductance 7.

In Fig. 1 I have illustrated the cylindrical member 16 as solid, whereas in Fig. 2 the cylindrical member 16 is shown slotted at 17 longitudinally along the length thereof. This cylinder is moved over the plate coil until oscillations are developed. The slotted cylindrical member 16 illustrated in Fig. 2 has an advantage over the solid cylindrical member 16 in Fig. 1 by reason of the decreasing of the losses in the oscillator system. The cylindrical member 16 is moved 105 110

to a selected point along coil 7 dependent upon the frequency to be sustained and upon the value of the fixed or variable capacity 11 which may be connected across the terminals of the winding 7. With the capacity 11 across the winding 7 omitted oscillations may be produced but the circuit offers such a high impedance with such a broad characteristic that it is difficult to 10 secure the desired fundamental oscillation of the piezo electric crystal element. The battery action from the plate circuit upon the coil circuit is substantially negligible and the oscillations of the true frequency of 15 the piezo electric crystal element are maintained. Circuit oscillations are avoided for frequencies other than that frequency sustained by the piezo electric crystal element 15.

20 My invention has been found to be extremely practical and efficient in its operation, and while I have described my invention in certain of its preferred embodiments, I desire that it be understood that modifications may be made and that no limitations 25 upon the invention are intended other than are imposed by the scope of the appended claims.

What I claim as new and desire to secure 30 by Letters Patent of the United States is as follows:

- 35 1. In a piezo electric crystal controlled oscillator system an electron tube having grid, filament and plate electrodes, an output circuit interconnected between said plate and filament electrodes, an inductance and a source of potential in said circuit, a pair of parallel electrodes, a piezo electric crystal element mounted between said parallel electrodes and a connection between one of said parallel electrodes and said grid electrode and a capacity connection between the other of said parallel electrodes and a variable point on said inductance.
- 40 2. A piezo electric crystal controlled oscillator including an electron tube having grid, filament and plate electrodes, an output circuit interconnected between said plate and filament electrodes with an inductance connected therin, a piezo electric crystal element, electrodes for establishing electrical

connection with the opposite surfaces of said piezo electric crystal element, a connection between one of said last mentioned electrodes and said grid electrode and a connection between the other of said last mentioned electrodes and a capacity area, said capacity area substantially surrounding the inductance in said output circuit.

3. A piezo electric crystal controlled oscillator including an electron tube having grid, filament and plate electrodes, an output circuit interconnected between said plate and filament electrodes with an inductance connected therein, a piezo electric crystal element, electrodes for establishing electrical connection with the opposite surfaces of said piezo electric crystal element, a connection between one of said last mentioned electrodes and said grid electrode and a connection between the other of said last mentioned electrodes, and a movable cylindrical member, said cylindrical member substantially including said inductance and slidably thereover in spacial relation with respect thereto to a selected position for sustaining oscillations of a frequency corresponding to the natural frequency of said piezo electric crystal element.

4. A piezo electric crystal controlled oscillator including an electron tube having grid, filament and plate electrodes, an output circuit connected between said plate and filament electrodes, a coil included in said output circuit, a conductive cylindrical member slotted on one side thereof and arranged to be moved to selected positions over said coil in capacity relation thereto, a piezo electric crystal element, a pair of electrodes for establishing connection with opposite faces of said piezo electric crystal element, a connection between one of said electrodes and said grid electrode, and a connection between the other of said electrodes and said conductive cylindrical members for completing the capacitive connection through said piezo electric crystal element whereby oscillations of a frequency corresponding to the natural frequency of said piezo electric crystal element may be sustained in said output circuit.

In testimony whereof I affix my signature.
AUGUST HUND.
